(57) CLAIM

The ornamental design for an engine-driven welding machine, as shown and described.

DESCRIPTION

The claimed engine-driven welding machine is used for welding in the outdoors, and instruments required for welding, such as an engine, a generator, and electrical components, are accommodated therein, and has handholds at both sides thereof. The engine-driven welding machine is easily moved to another place or load on a vehicle by pulling it using handholds. A terminal cover is pivotably attached through the hinge etc., and is swung downwardly for covering terminals at the time of non-using.

FIG. 1 is a front elevational view of an engine-driven welding machine showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front perspective view thereof;

FIG. 8 is a rear perspective view thereof;

FIG. 9 is referential top plan view thereof, wherein each doors are opened; and,

FIG. 10 is a referential front elevational view thereof, wherein a terminal cover is opened.
